HEEL BOOM ATTACHMENT FOR POWER SHOVELS

Reid G. Priest, Port Angeles, Wash.

Application June 18, 1958, Serial No. 742,780

6 Claims. (Cl. 214—147)

This present invention relates to the logging industry and more particularly to an attachment for use on normally self-propelled power shovels and like equipment and most especially to a heel boom arrangement for handling logs in loading trucks and the like whereby the entire heel boom arrangement and supported log can be moved longitudinally of the truck bed in addition to have the various movements which the power shovel mechanism normally employs in the handling of its excavating dipper and the like.

Present day logging operations as applied to the larger logs of first growth timber especially involves the use of a tremendous amount of expensive power equipment. The amortization of the investment in this equipment, which rapidly depreciates is one of the major items in the cost of producing saw logs from virgin timber. The better stands of timber today are in those areas that formerly were considered to be difficult of access and this requires the logging operator to build and maintain his own roads and do all things necessary in the handling of his logs from the sawing of the same to the delivery of them to a point where they can be either delivered to saw mills or delivered to transportation facilities that in turn will deliver them to mills. This present invention, relating as it does to an attachment to such machines as the larger power shovels and the like makes it possible to use, for a greater part of the time, a very expensive yet essential piece of equipment which usually is used only at widely spaced intervals. By applying an attachment to an intricate piece of equipment that is practically standard with all large logging operations, a degree of handling agility can be achieved that is not at all possible with the usual arrangement of using the heel boom loading equipment.

A principal object of this present invention, therefore, is to provide a heel boom attachment for power shovels and the like which will take fullest advantage of the intricate, highly developed and expensive equipment which is present in the power shovels.

A further object of this invention is to provide an attachment for power shovels and the like wherein the log engaging platform is supported near its center of mass by pivoted suspension members, the upper pivots of which are attached to the outer end of the steam shovel boom, and having the inboard end of a heel boom arrangement secured to the manipulatory arm of the steam shovel, to which normally the excavating bucket is secured.

A further object of this present invention is to provide a heel boom attachment for power shovels that has the capacity of effecting all movements normally attributed to the heel boom loading arrangement but which, in addition, has increased capacities and movements obtained by making use of the intricate mechanism and control means of the highly developed power shovels.

Further objects, advantages and capabilities will be apparent from the description and disclosure in the

2

drawings, or may be comprehended or are inherent in the device.

In the drawings:

Figure 1 is a perspective view illustrating the loading of large logs and showing my attachment as it is normally employed with a conventional track laying power shovel.

Figure 2 is a fragmentary side elevation, partly in section showing the additional maneuverability of my attachment by showing the arc through which the attaching pivots of the suspension members can travel and showing the positioning of the attachment when taking full use of the translating mechanism of the power shovel bucket arm, one position being shown in dashed lines.

Figure 3 is a perspective view illustrating the essential components of my heel boom attachment and showing it in its association with certain parts of the power shovel. Some parts are broken away and sectioned.

Figure 4 is a fragmentary view, partly in section and illustrating in perspective arrangement a slack pulling device which under certain conditions is desirable for use with my attachment.

Figure 5 is an elevation, partly in section, showing the extreme outboard end of my heel boom attachment and illustrating the sheave employed with the log raising cable.

Figure 6 is a top plan view, partly in section, illustrating the manner in which my attachment is secured to the end of the shovel bucket arm and illustrating the strength of this attachment, which is very desirable.

Figure 7 is a fragmentary side elevation, showing the normally horizontal portion of my attachment with the upwardly directed portion as the same would be seen if viewed from the line 7—7 of Figure 3.

Figure 8 is a fragmentary vertical view partly in section taken along the line 8—8 of Figure 3.

Referring to the drawings, throughout which like reference characters indicate like parts, the numeral 10 designates generally my heel boom attachment. This unit is provided with a log heel rest or platform portion, made up of a plurality of closely spaced transversely disposed structural steel members, as the members 12 and 14, forming the end members and a plurality of members 16 intermediately disposed between the end members. These transverse members are all fixedly secured, as by welding thereto, to the longitudinal structural steel members 20. This platform arrangement must be ruggedly constructed as it takes not only the weight of heavy logs under conditions of very unfavorable mechanical advantage but it also must accept a great deal of shock loading as when the end of the heavy logs collide with it.

Supported to the outer end of the platform and with its members preferably welded to the transverse beam 14 and the longitudinal beams 20, is the outer guide or outboard portion of the boom attachment. This member, again must be generously proportioned, as it must take not only the shock loading of guiding the logs as they are picked up for positioning in the heel boom attachment, but it also must support a weight normally in excess of the weight of the log lifted, due to the fact that the log in itself becomes a first class lever and the point where the lifting tongs T is attached is toward the butt end of the log which normally will be engaged by the heel boom platform. In this type of operation, it is, of course, always necessary that the outer end of the log will be preponderantly heavy and thus urge the end of the log in contact with the platform into a very secure engagement with it.

It is also necessary that the cable sheave 30 be posi-

tioned substantially above the plane of the platform in order to provide operational room for the tongs T. In the present drawings, a preferred arrangement of this outboard end is illustrated in which the side guard members, as 32 and 33, are secured to the front face of the transverse beam 14 and the central beams 35 and 36 are secured to the longitudinal beams 20 so that there is some angularity between the beams 32, 33, 35 and 36. This relationship is probably best shown in Figure 7. This arrangement gives increased strength due to the overall depth of the structural members. At a point toward the outer end from the longitudinal center of the outboard portion of my attachment is provided an additional transverse strengthening member 40. This member forms an end abutment for the longitudinals 35 and 36 on one side and a point of attachment for the prolongation members 42 and 43. A preferred, although not an essential construction, except in the larger sizes, is to provide a change of angle at this point substantially after the showing of Figure 8 in the drawings. At its extreme end the outboard end framework is provided with the end cross member 44 which serves to join the various members together and to provide protection for sheave 30 and its supporting shaft 31 and also the guide shaft 46 which may under certain conditions carry additional sheaves for guiding purposes, the same not being shown in the present drawings.

Referring particularly to Figures 3 and 6, a preferred means for coupling my attachment to the conventional bucket arm 50 is illustrated. The bucket arm 50 is the manipulatory arm of the power shovel. Normally it is provided with cable supporting means at its extreme outer end so that it may be swung vertically by that means, pivoting in the rockable bearing assembly 52. This outer end cable, that is normally employed, is not employed with my attachment. This change in the equipment of the power shovel frees the large sheaves 54 and 55, one of which, as 54, is normally not employed with my attachment. The sheave 55 is employed as a matter of convenience to handle the log lifting cable C. The second control element for arm 50 as generally used is the rack gear 56 and its coacting mating pinion 58 revolvably supported and driven by shaft 59 and suitable sprockets secured thereto, which is power driven from suitable source, as by the chains 60.

With my present attachment and as a very important part of my invention I employ, as a substitute for the cable raising means of the outer end of arm 50, the two suspension members as 62 and 63. These members, which must be able to accept as struts, all the shock loading occasioned by the log L abutting the heel engaging platform, must also support the entire weight of the attachment and the end of arm 50 in addition to a component of the force exerted by cable C in the log raising or lowering operations. They must therefore be generously proportioned and provided with adequate pivot bearings. The upper pivots 64 which must be axially aligned may make use of the sheave supporting shaft 66 or they may have separate pivots as long as they are in axial alignment with each other and parallel to shaft 66. At the lower ends the suspension and strut members 62 and 63 are pivotally secured at 68 and 69, preferably to the inner end transverse member 12, this relationship being quite well shown in Figures 2 and 3.

The outer end of the shovel arm 50, after the bucket or other excavation device is removed, is secured, preferably, to the longitudinal structural member 20 of my attachment. This construction is illustrated in its assembled form in Figure 3 and in fragmentary form on a larger scale in Figure 6. In this arrangement, the spaced bolts, better referred to as shafts 70 and 72, each pass through arm 50 and through each of the parallel structural members 20. They are secured in place by suitable nuts or collars 74 and may employ spacer members as 76 so that a very secure connection will be formed be-

5 tween arm 50 and my attachment 10. No attempt has been made to show specific details of arm 50 as this structure is not critical with my invention and will be found to vary in structural form in keeping with the 10 engineering of the various makers of this type of equipment.

When assembled, my attachment 10 is supported by means of suspension members 62 and 63 and by the rockable bearing 52 which guides and supports the 15 bucket arm 50. Boom B of course is one of the major components of the conventional power shovel and is pivotally mounted on the carriage of the shovel in a very substantial manner. With special emphasis, normally placed on shock loading, because of the usual shock incidental to excavation work these design features lend themselves admirably to the conditions under which the shovel is employed when my device is put to use. The outer end of boom B is cable supported as by cables S and U. These cables pass over suitable sheaves supported from shaft 66 and are led back to power operated drums under the control of the operator of the power shovel P. With my attachment, this normal functional part of the power shovel is employed. The normal functioning of boom B in raising or lowering the outer 20 end of the boom is a very desirable part of my present device and its functioning in that it permits lowering the entire attachment and the log, that it may have raised to the position shown in Figure 1, and can then accurately position the log on the truck or rail car with which 25 it is to be transported.

30 In certain cases, it is desirable to have means for pulling slack in cable C. This may result from tongs T not being heavy enough to pull the slack, or the cable C may be of such a diameter that it becomes difficult for the 35 hook tender to pull the slack required. In such a circumstance the slack puller that is illustrated generally in Figure 4 may be employed, and this is usually employed near the upper end of boom B as illustrated at 80 where it is normally positioned on a bracket or seat disposed between the two side members as 82 and 84 of boom B. These devices, which are in effect a friction drive for the 40 cable C are normally operated by fluid motors, which are not illustrated as this equipment is quite highly 45 standardized and is not an essential part of this invention. The fluid lines as 86 and 87 provide for the fluid under pressure supplied to the drive means and its return.

Method of operation

50 It is believed that the general operation of my equipment will be understood to a degree at least from a study of Figures 1 and 2. The power shovel unit P is positioned so that the boom arrangement will be able to reach logs that have been yarded into a central point adjacent truck roads and then the unit must still be able to deposit the log on the transport unit, such as the truck and trailer illustrated in Figure 1. Heel boom loading devices in the past have taken on many forms. In some cases they are a specialized unit installed in a 55 fixed position as at a saw mill or the like or they may be employed as a self-propelled unit, in which case it has been common to employ a revolvable power unit and have mounted upon it a heel boom arrangement which would be similar to the structure of Figure 3 if it were arranged that my attachment were fixedly secured to boom B. Such arrangements have proven to be of great 60 value in the handling of logs and far safer and quicker in their operation than the various type of derrick or gin pole arrangements.

65 With my present equipment, however, a much more flexible unit is provided that provides an exact and convenient handling of logs that cannot be achieved by the usual heavy unit as currently employed. One great advantage of this present equipment is illustrated in the flexibility of the equipment as shown in Figure 2 in that the whole attachment, including the platform which

engages the inboard end of the log is capable of being positioned without raising or lowering the boom or having the power unit move upon its track-laying arrangement. Neither one of these usual movements gives exact, convenient or quick handling capacities which can be so easily achieved merely by the operation of the standard component of the power shovel, as its manipulatory arm 50, which is a highly developed piece of equipment and designed for exact positioning of an excavation bucket. This same equipment is employed to give exact placement of log L without the necessity of moving the entire power equipment or of making adjustments of the angular position of the main boom itself. A high degree of control is provided when it is only necessary to raise and slack off on cable C and to move the entire assembly longitudinally by the operation of arm 50. In Figure 2 an extreme position is shown in dashed lines but for most loading operations it only needs a movement of two or three feet as a rule to actually position a log and this range is provided in almost a straight line operation because two or three feet of the arc 90 is for all practical purposes a straight line. In general the heel boom operation otherwise is quite similar to conventional equipment and the contribution effected in this present application is to provide equipment of this order as a relatively inexpensive attachment for use with equipment that the average successful logging operator already has on hand, namely, his power shovel. There is, however, an additional great advantage achieved, particularly by the use of the swinging suspension members 62 and 63 which enables the normal translating gear as the rack 56 and drive pinion 58 of arm 50 to supply a nicety of control that usually is not considered possible in equipment that must handle the tremendously heavy loads required to handle the logs cut from first growth timber stands.

It is believed that it will be clearly apparent from the above description and the disclosure in the drawings that the invention comprehends a novel construction of a heel boom attachment for power shovels.

Having thus disclosed the invention, I claim:

1. A heel boom attachment for power shovels, comprising: a log heel platform formed of longitudinally disposed and transversely disposed metal structural members which are rigidly joined together to form a platform to act as a rest for one end of a log as it is being raised; a sheave support and log guide member fixedly secured to said platform and inclined upwardly from the plane of said platform; a sheave revolvably supported at the outer end of said support and guide member to operatively position a log lifting cable; a power shovel boom having spaced side members, pivotably supported from said shovel; means for raising or lowering the outer end of said boom; a plurality of suspension members pivotably secured adjacent the inner end of said platform and extending upwardly and pivotably secured to said spaced side members near the outer end of said boom; a power shovel bucket arm pivotably secured to said boom intermediate the ends of said power shovel boom; joining means adapted to fixedly secure the outer end of said bucket arm to said platform; means for extending or retracting said bucket arm with respect to said boom and provide that the point of attachment of said suspension members to said platform, will swing in an arc about the upper pivots of said suspension arms; power means for moving said bucket arm; power means for positioning said boom and power means for operating said log lifting cable.

2. A heel boom attachment for power shovels, comprising: a log heel platform formed of longitudinally disposed and transversely disposed metal structural members which are rigidly joined together to form a platform to act as a rest for one end of a log as it is being raised; a sheave support and log guide member fixedly secured to said platform and inclined upwardly from

the plane of said platform; a sheave revolvably supported at the outer end of said support and guide member to operatively position a log lifting cable; a power shovel boom having a plurality of aligned horizontal pivots on the base of said power shovel and thereby supported at one end from said shovel; cable means, operable from said shovel, for raising or lowering the outer end of said boom; a plurality of suspension members pivotably secured adjacent the inner end of said platform and extending upwardly and pivotably secured to said spaced side members near the outer end of said boom; a power shovel bucket arm pivotably secured to said boom intermediate the ends of said power shovel boom; joining means adapted to fixedly secure the outer end of said bucket arm to said platform; means for extending or retracting said bucket arm with respect to said boom and provide a third point of support for said platform to stabilize it as it swings in an arc about the upper pivots of said suspension arms; power means for moving said bucket arm; power means for positioning said boom and power means for operating said log lifting cable.

3. A heel boom attachment for power shovels, comprising: a log heel platform formed of longitudinally disposed and transversely disposed metal structural members which are rigidly joined together to form a platform to act as a rest for one end of a log as it is being raised; a sheave support and log guide member fixedly secured to said platform and inclined upwardly from the plane of said platform; a sheave revolvably supported at the outer end of said support and guide member to operatively position a log lifting cable; a power shovel boom having spaced side members, pivotably supported from said shovel; cable means for raising or lowering the outer end of said boom; a suspension member pivotably secured adjacent the inner end of said platform and extending upwardly and pivotably secured near the outer end of said boom; a power shovel bucket arm pivotably secured to said boom intermediate the ends of said power shovel boom; joining means adapted to fixedly secure the outer end of said bucket arm to said platform; a rockable bearing assembly for slidably supporting said bucket arm from said boom; gear means for extending or retracting said bucket arm with respect to said boom and provide that the point of attachment of said suspension members to said platform, will swing in an arc about the upper pivot of said suspension arm; power means for moving said bucket arm; power means for positioning said boom and power means for operating said log lifting cable.

4. A heel boom attachment for power shovels having a revolvable machinery and operator's cab, comprising: a log heel platform formed of longitudinally disposed and transversely disposed metal structural members which are rigidly joined together to form a platform to act as a rest for one end of a log as it is being raised; a sheave supporting framework fixedly secured to said platform and inclined upwardly from the plane of said platform; a sheave revolvably supported at the outer end of said support to operatively position a log lifting cable; a power shovel boom pivotably supported from the revolvable cab of said shovel; cable means for raising or lowering the outer end of said boom; a plurality of suspension members pivotably secured adjacent the inner end of said platform and extending upwardly and pivotably secured to said spaced side members near the outer end of said boom; a power shovel bucket arm pivotably secured to said boom intermediate the ends of said power shovel boom; joining means adapted to fixedly secure the outer end of said bucket arm to said platform; means for extending or retracting said bucket arm with respect to said boom and provide that the point of attachment of said suspension members to said platform, will swing in an arc about the upper pivots of said suspension arms; power means for moving said

bucket arm; power means for positioning said boom and power means for operating said log lifting cable.

5. A log handling, heel boom attachment for power shovels, comprising: spaced apart longitudinal structural beams having a straight, substantially horizontal platform portion and an annularly disposed upwardly directed guide portion; a plurality of closely spaced transverse structural beams fixedly secured to the platform portion of said longitudinal beams to provide a log heel rest platform; a plurality of transverse structural beams fixedly secured to said upwardly directed portion of said longitudinal beams to provide a log guide portion of said boom attachment; a log lifting cable sheave disposed on a transversely disposed shaft secured to said log guide portion; a power shovel bucket arm operatively secured to a power shovel and having means for fixedly securing the outboard end of said arm to said log rest platform; a power shovel boom adapted to be pivotably secured to a power shovel and to move in a vertical plane; a power shovel having power means and means for revolving said power shovel and said shovel boom in a horizontal plane; a pair of spaced rigid suspension members pivotably secured to opposite sides of said boom and to opposite sides of said log heel rest platform on an inner end transverse beam; said suspension members of sufficient strength to support the entire weight of said log rest platform and a log as it is being raised and being moved along a vertical arcuate path in a loading sequence; and a log raising cable adapted to pass over said sheave and power means for operating the cable.

6. A log handling, heel boom attachment for power shovels, comprising: spaced apart longitudinal structural beams having a straight, substantially horizontal platform portion and an annularly disposed upwardly directed guide portion; a plurality of closely spaced transverse structural beams fixedly secured to the platform portion of said longitudinal beams to provide a log heel rest platform; a plurality of transverse structural beams, in-

cluding an end cross member, fixedly secured to said upwardly directed portion of said longitudinal beams to provide a log guide portion of said boom attachment; side guard members secured at one end to the outer margin of said platform and converging to their opposite ends where they are secured to said longitudinal beams; a log lifting cable sheave disposed on a transversely disposed shaft secured to said log guide portion within the framework of said guide portion and behind said end cross member; a power shovel bucket arm operatively secured to a power shovel and having means for fixedly securing the outboard end of said arm to said log rest platform; a power shovel boom adapted to be pivotably secured to a power shovel and to move in a vertical plane; a power shovel having power means and means for revolving said power shovel and said shovel boom in a horizontal plane; a pair of spaced rigid suspension members pivotably secured to opposite sides of said boom and to opposite sides of said log heel rest platform on the inner end of said log heel rest platform; said suspension members of sufficient strength to support the entire weight of said log rest platform and a log as it is being raised and being moved along a vertical arcuate path in a loading sequence; and a log raising cable adapted to pass over said sheave and power means for operating the cable.
